INVENTOR

J. F. Stirling.

UNITED STATES PATENT OFFICE.

JOHN F. STERLING, OF SAN FRANCISCO, CALIFORNIA.

WATCH-KEY.

Specification of Letters Patent No. 26,450, dated December 13, 1859.

To all whom it may concern:

Be it known that I, JOHN F. STERLING, of the city and county of San Francisco and State of California, have invented a new and useful Improvement for Keys, which I call "Sterling's Improved Key;" and I do hereby declare that the following is a full, clear, and exact description of the construction and operation of the same, reference being had to the annexed drawings, making a part of this specification, in which—

Figure 1, represents the key of a door lock. Fig. 2, represents a section of the same. Fig. 3, represents a watch key. Fig. 4, represents a section of the same.

My invention consists in a watch or door key as a new article of manufacture viz: with a hollow pod or shank open at both ends, so that any dirt that may get into the pod or shank may work through to the opposite end and drop out, and not become clogged therein.

To enable others skilled in the art to make and use my invention, I will proceed to describe the same with reference to the drawings.

In Figs. 1 and 2, I have represented a door or lock key constructed after my plan the stem or shank thereof being hollow all the way through, as seen at *a* in Fig. 2. Any dirt that may get into the stem will drop or be forced through to the opposite end, and thus not lodge in the key, and prevent it from properly operating in its lock, as often happens.

In Figs. 3, and 4, I have shown the same principle applied to watch keys, the stem thereof being hollow and open at both ends, as shown at *a* in Fig. 4, so that any dirt getting into the key will pass or be driven out at the open end thereof.

What I claim as my invention, and desire to secure by Letters Patent is—

As a new article of manufacture a watch or door key with a hollow stem or pod, open at both its ends, so that anything getting into it that would obstruct its action, will drop or be pushed out, through the open stem as set forth.

J. F. STERLING.
